UNITED STATES PATENT OFFICE.

JAMES H. DONALDSON AND HARRY H. SCHROYER, OF CHICAGO, ILLINOIS, ASSIGNORS, BY DIRECT AND MESNE ASSIGNMENTS, TO THEMSELVES AND E. J. WARD COMPANY, OF CHICAGO, ILLINOIS, A CORPORATION OF ILLINOIS.

DIAPHRAGM FOR CAR-VESTIBULES.

SPECIFICATION forming part of Letters Patent No. 695,918, dated March 25, 1902.

Application filed August 22, 1901. Serial No. 72,891. (No model.)

To all whom it may concern:

Be it known that we, JAMES H. DONALDSON and HARRY H. SCHROYER, citizens of the United States, and residents of Chicago, in the county of Cook and State of Illinois, have invented certain new and useful Improvements in Diaphragms for Car-Vestibules; and we do hereby declare that the following is a full, clear, and exact description thereof, reference being had to the accompanying drawings, and to the letters of reference marked thereon, which form a part of this specification.

This invention relates more particularly to vestibule - diaphragms for cars or the like constructed from a plurality of strips firmly joined edge to edge to provide the usual extensible accordion folds or plaits.

The object of the invention is to provide a construction at once cheap, attractive, and durable and of great strength, thereby being practically self-sustaining or, in other words, holding the same from sagging or getting out of position when in use.

The invention consists in the matters hereinafter described, and more fully pointed out and defined in the appended claims.

In the drawings, Figure 1 is a perspective view of a part of a car-vestibule provided with a diaphragm embodying our invention. Fig. 2 is a horizontal section through one side or leg of the diaphragm. Figs. 3 and 4 illustrate means for fastening the seams. Fig. 5 is a view similar to Fig. 2 with the wires omitted. Fig. 6 is a perspective view of one of the strips of diaphragm material formed ready for use. Fig. 7 is a perspective view of a diaphragm constructed of a plurality of strips such as shown in Fig. 6. Fig. 8 is a horizontal section through one of the legs of the diaphragm illustrated in Fig. 7.

As shown in said drawings, said diaphragm is constructed of a plurality of strips A and A', of fabric or other suitable material, having a width slightly greater than the folds of a completed diaphragm. Said strips are each folded along one margin to form the overlap a a', which is adapted to engage over the plain or unfolded edge of the adjacent strip, as shown in Fig. 2. Said corners or seams are

then permanently closed by riveting, stapling, 50 sewing, or the like through said overlap and through both of the strips to form a permanent seam. Said strips A and A' may obviously be cut of any desired length, and, if preferred, the same may be woven or otherwise constructed so as to form the top and each leg of a diaphragm - fold integrally from a single strip, thereby avoiding transverse seams at the turns or bends at each upper corner of the diaphragm. Inasmuch as said strips may be 60 composed of a fabric similar to cotton-burlap and of two or more ply, it is obvious that the thickness of the seams and stiffness of the material form a stay, greatly increasing the strength of the diaphragm and tending to prevent the top sagging out of position. As a further improvement a strong rod or wire (indicated by B and B') is inclosed in each of the longitudinal seams on the outer and inner sides of the diaphragm and extends over 70 the top and down each side of the same, as shown in Figs. 2 and 8, and forms a rigid support for the diaphragm vertically.

Obviously it is not essential that the strips used in the construction of the diaphragm 75 be approximately equal to the width of the diaphragm. The same may conveniently be constructed of approximately double the width of the diaphragm. As shown in Figs. 6, 7, and 8, a single strip forms two folds. 80 In this construction the strips of fabric of which the diaphragm is composed are shown woven or otherwise constructed to conform to the general shape of the diaphragm. Each of said strips A' has a narrower and a wider 85 side c c', respectively, of which the latter is folded over at its margin to form the overlap c' to receive the next succeeding lap c, as shown in Fig. 8. As shown, the wires B and B' may conveniently be used in this construction, as shown in Fig. 8. Said seams may be riveted, stapled, or otherwise permanently closed.

Obviously many different materials may be used in the construction of diaphragms embodying our invention, and many details of construction may be varied without departing from the principle thereof.

We claim as our invention—

1. A diaphragm for vestibules, comprising a plurality of strips of fabric each having one edge bent over longitudinally and forming a 5 lap-seam in which is engaged the margin of the next adjacent strip by means of rivets or the like.
2. A diaphragm for vestibules, comprising a plurality of strips of fabric each having one 10 edge bent over longitudinally and forming a lap-seam in which is engaged the margin of the next adjacent strip by means of rivets or the like and a rigid strip secured in said lap-seam.
- 15 3. A diaphragm for car-vestibules, comprising a plurality of strips of material bent longitudinally at one of its edges and forming a lap-seam with a corresponding strip, said strips being constructed integrally to 20 form to the curvature of the top of the diaphragm.
- 25 4. In a car-diaphragm, a plurality of strips of fabric each having one edge bent longitudinally thereof and adapted to receive and lap over the edge of an adjacent strip, a rod secured in said bend or fold and means passing through and through said strips and said lap and acting to bind the same rigidly together.

5. In a car-diaphragm, a plurality of strips 30 each formed to correspond with the general contour of a diaphragm-section and comprising two unequal sides or parts, one of which is folded or bent longitudinally to receive and form a lap-seam with the plane portion 35 of the next adjacent strip, a metallic rod secured in each fold or bend of the diaphragm thus formed and extending along the sides and top of the same.

6. In a car-diaphragm, a plurality of strips 40 each formed to correspond with the general contour of a diaphragm-section and comprising two unequal sides or parts, one of which is folded or bent longitudinally to receive and form a lap-seam with the plane portion of 45 the next adjacent strip and metallic rods enclosed in each seam and extending across the top of the diaphragm and down each side thereof.

In testimony whereof we have hereunto subscribed our names in the presence of two subscribing witnesses.

JAMES H. DONALDSON.
HARRY H. SCHROYER.
